To all whom it may concern:

Be it known that I, Nicolo Alba, a citizen of the United States, residing at Brooklyn, in the county of Kings and State of New York, have invented a new, original, and ornamental Design for a Souvenir Cake Box or the like, of which the following is a specification, reference being had to the accompanying drawing, forming part thereof.

Figure 1 is a top perspective view of a souvenir cake box or the like, showing my new design;

Figure 2 is a side elevational view thereof; and

Figure 3 is a bottom plan view thereof.

The essential features of my design reside in the portions shown in solid lines.

I claim:

The ornamental design for a souvenir cake box or the like, as shown and described.

NICOLO ALBA.
